[57] CLAIM

The ornamental design for a ignitor disposed within an harbor formed by a sealed gas burner, as shown and described.

DESCRIPTION

FIG. 1 is a perspective view of an ignitor disposed within a harbor formed by a sealed gas burner showing my new design;

FIG. 2 is a front elevational view thereof;

FIG. 3 is a top plan view thereof; and,

FIG. 4 is a rear elevational view thereof.

The portions shown in broken lines in FIGS. 1 through 4 are shown for illustrative purposes only and form no part of the claimed design. The undisclosed bottom is plain and unornamented.
